UNITED STATES PATENT OFFICE

ERNEST C. DANIELS, OF ORANGEVILLE, ONTARIO, CANADA

VENTILATOR

Application filed July 31, 1929, Serial No. 382,386, and in Canada March 25, 1929.

This invention relates to devices adapted to be either permanently or detachably secured to the upper part of a window, provided with a vertically sliding pane, to provide an air 5 exit and my object is to devise a simple and inconspicuous ventilator of this type controllable by the raising or lowering of the sliding pane.

I attain my object by providing a hood 10 adapted to be fitted at the top of the window frame and having a bottom extending inwardly towards the outer surface of the sliding pane. In this bottom are formed ventilating openings of louver-like form. To 15 the inner side of the hood is secured a flexible strip contacting with the sliding pane. Preferably the tongues are of such a width that the walls of the hood form the inner and outer sides of the louvers. In the inner wall 20 are formed suitable openings through which air passes to the interior of the vehicle.

The device is constructed in detail substantially as hereinafter more specifically described and as illustrated in the accompanying 25 drawings in which

Fig. 1 is a vertical section showing my device applied to a window; and

Fig. 2 a perspective view of part of the device on a larger scale.

30 In the drawings like numerals of reference indicate corresponding parts in the different figures.

In the drawings 1 is a frame in which is 35 slidably mounted the glass pane 2. Secured to or forming part of the top of the frame is the ventilator hood, which is integrally formed of sheet metal bent to U-form, 3 being the outer wall, 4 the inner wall, and 5 the bottom, which extends comparatively 40 close to the pane 2.

In this bottom are formed a series of openings 5^a through which air may pass. As it is desirable that the passage of air should be from within outward, these openings are 45 formed as louvers so that the movement of the vehicle, to which the device is applied, causes air to be drawn outwardly through the openings. These louvers are preferably formed by stamping up tongues 6 from the metal of the flange, which tongues are so posi-

tioned that the outer wall forms the outer side of each louver and the inner wall the inner side. Above the louvers suitable openings 8 are formed in the wall 4. Secured to the inner wall 4 is a flexible strip 10 of rubber or other suitable material which is adapted to engage the outer surface of the glass pane 2, thus preventing the inward passage of air between the ventilating device and the glass pane. This strip may be of any suitable form and secured in any suitable manner. I show it as of L-form, one leg of which contacts with the glass pane while the other is clipped to the wall 4 by means of tongues 7 stamped up from the metal of the wall. 55

The control of the ventilation is through the medium of the glass pane, which will be more or less raised in the usual manner to give a wider or narrower opening above the pane beneath the hood. 60

From the above description it will be seen that this construction of the device is very simple, as it can be entirely constructed of stamped sheet metal and readily applied to or built in the window frame. 65

What I claim as my invention is:

1. A ventilator for a window provided with a sliding pane comprising a hood adapted to be fitted at the top of the window frame and formed of sheet metal bent to U-form 70 and having a bottom extending inwardly towards the outer surface of the sliding pane, the bottom and inner wall of the hood having ventilating openings formed therein. 75

2. A ventilator for a window provided with a sliding pane comprising a hood adapted to be fitted at the top of the window frame provided with an open side adjacent the window and having a bottom extending inwardly towards the outer surface of the sliding pane, the bottom having louvers formed therein at right angles to the pane. 80

3. A ventilator for a window provided with a sliding pane comprising a hood adapted to be fitted at the top of the window frame provided with an open side adjacent the window and having a bottom extending inwardly towards the outer surface of the sliding pane, the bottom having louvers formed therein at right angles to the pane and a flexi- 85

ble weather strip secured thereto adjacent the pane.

4. A ventilator according to claim 2 in which the louvers are formed by stamped up tongues integral with the bottom and located close to the outer wall of the hood which thus forms one side of each louver and the other side of each louver is formed by upstanding portions integral with the bottom.

5. A ventilator according to claim 2 in which the louvers are formed by stamped up tongues integral with the bottom and located close to the outer wall of the hood which thus forms one side of each louver; the other side of each louver is formed by upstanding portions integral with the bottom; and a flexible window pane engaging strip is provided clipped to the inner side of the ventilator.

6. A ventilator according to claim 2 in which the louvers are formed by stamping tongues out of the bottom close to the outer wall of the hood which thus forms one side of each louver; and means are provided closing the inner side of said louvers.

7. A ventilator according to claim 2 in which the louvers are formed by stamping tongues out of the bottom close to the outer wall of the hood which thus forms one side of each louver; means are provided closing the inner side of said louvers; and a flexible window pane engaging strip is provided clipped to the inner side of the ventilator.

8. A ventilator hood formed of sheet metal bent to U-form, the outer wall being imperforate, louvers being formed in the bottom by integral tongues cut from the bottom and bent up, and openings formed in the inner wall above the louvers.

9. A ventilator hood formed of sheet metal bent to U-form, the outer wall being imperforate, louvers being formed in the bottom by integral tongues cut from the bottom and bent up, openings formed in the inner wall above the louvers, and a flexible strip secured to said inner wall.

Signed at Toronto, Can., this 24th day of July, 1929.

ERNEST C. DANIELS.
